(57) CLAIM

The ornamental design for a box for cosmetic products as shown and described.

DESCRIPTION

FIG. 1 is a perspective view of the box for cosmetic products showing our design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Evenly broken lines are shown for the purpose of illustrating parts of the box for cosmetic products which form no part of the claimed design. The dot-dash broken lines represent the boundaries of the claim and form no part thereof.

1 Claim, 7 Drawing Sheets
